Fig.5

FIG. 1 is a side elevational view of a bottle or similar article embodying my new design;

FIG. 2 is a top plan view thereof;

FIG. 3 is a bottom view thereof;

FIG. 4 is a front view thereof; and

FIG. 5 is a rear view thereof.

The characteristic features of my design reside in the open cargo carrying portion in combination with the truck cabin and body frame posterior to the truck cabin wherein the open cargo carrying area with cargo disposed therein is of a height approaching the height of the uppermost portion of the truck cabin and is separated from the truck cabin by a buffer zone, as shown.

This application is a division of my earlier filed application Serial No. D77,291 filed November 5, 1963 now U.S. Patent D.200,737 patented March 30, 1965.

I claim:

The ornamental design for a bottle or similar article, as shown and described.
